UNITED STATES PATENT OFFICE.

RUFUS C. BEARDSLEY, OF ELKHART, INDIANA.

DAM.

SPECIFICATION forming part of Letters Patent No. 733,123, dated July 7, 1903.

Application filed December 27, 1902. Serial No. 136,813. (No model.)

To all whom it may concern:

Be it known that I, RUFUS C. BEARDSLEY, a citizen of the United States of America, residing at Elkhart, in the county of Elkhart and State of Indiana, have invented new and useful Improvements in Dams, of which the following is a specification.

My invention relates to improvements in dams, which are set forth in this specification and shown in drawings, Figures 1, 2, 3, 4, 5, and 6, the object of the invention being to obstruct the flow of streams and rivers and to confine and raise the waters therein in the most efficient manner.

The improvements consist of a breastworks resting upon the lower mat *s* and composed of the posts *f* and the plank *g*. Said breastworks extends across the full length of the dam and is sustained by the cleats *o* and the plank *u*. When the height of the dam is great, the posts *f* are braced from the deck *e*. With this arrangement I do away with all rods which might conduct the water to the edge of the mat. By placing the breastworks on the lower mat the top of the posts *f* are lowered below the surface of impounded water by the depth of the sill *v* and the plank *u*, which in the case of low dams is very important, as otherwise ice or driftwood might strike against them. A single thickness of plank being more pliable than two thicknesses, the piling *n* may be fastened to the mat, the flexibility of the plank *s* allowing the mat under the dam to press with more force upon the underlying gravel than would be the case if the top floor of mat extended to the piling. All river-bottoms will not require the use of this breastworks. I therefore wish it to be considered as an entirely separate device from the foundation-mat.

The improvement in the mat (by which I mean that part of the structure upon which the dam proper and the breastworks rest) consists of the arrangement of the sills *p* and *v*, Figs. 1 and 2, Fig. 1 being a plan view and Fig. 2 an end elevation. It will be seen that the planks *r* run across the river lengthwise with the dam and are laid loosely together and nailed to the sills *p*, which run at right angles with the length of dam. The timbers *p* are spaced so that they come under the dam-sills *c* and are fitted tightly between the sills

v, thus dividing the interior of mat into water-tight boxes. The planks are laid either single or double and laid in close contact, so as to be nearly as possible water-tight. This arrangement gives a more uniform distribution of pressure and tends to localize any leakage. The compartments between the sills *p* are filled with earth or cement. The cant-board *i* is made to project above the plank *u* to form a dam in such a manner that water is held on top of the mat, as shown in Fig. 2. This water fills the compartments formed by the sills *p* and *v*, and thus preserves the entire mat from decay. This I call a "submerged" mat.

Heretofore the decking of dams has been put together with spikes or bolts; but I have found that these hold the planking apart after the water has thoroughly seasoned and shrunk them and that they in time form leaks. To obviate the difficulty, I have invented the decking shown in Figs. 4 and 6, in which *e* is a plank in which are cut grooves on each edge. *n* is a tongue of soft dry wood so proportioned that it fits closely in these grooves and holds the plank *e* apart a distance depending on the head of water the deck is to sustain. With this arrangement the hydraulic pressures are made to act on the tongue, pressing it with great force against the grooves in the plank. There being no nails to rust or hold the tongue away, the joints will at all times remain tight.

I claim an improvement in a ventilated dam. At one or both ends of dam an opening *t*, Figs. 1 and 2, through the abutment *h* is provided. This opening may be of any size or shape, and I do not wish to restrict my invention to the exact location of this opening, but reserve the right to make such changes therein as are not at variance with the spirit of the invention. The object of said opening is to allow of the free admission of air and also persons and materials. It has been proven that water pouring over the crest of a dam exhausts the air from under the dam, causing vacuums and dangerous pressures. It is to prevent the formation of vacuums and at the same time ventilate and allow of the inspection of the interior of the dam that the openings *t* are left.

Along the downstream edge of mat and ex-

tending across the river is provided a flexible mat, which I claim to be an improvement. This flexible mat is shown in detail in Figs. 3 and 5 and consists of a series of boxes 5 made as shown and bound together by rods or chains *z* and held to the mat-sill *g* by a bolt and ring *l*. Each box is made by nailing the plank *k* onto the square block of wood *T*, which acts as a plug. A hole is 10 bored through the plank and plug at each end of box, and then the different boxes are strung on the chains or rods *z*, thus forming a continuous and flexible mat. The boxes are then filled with sand through auger-holes 15 bored in the top plank to cause them to sink when they are undermined by water discharged from the dam until they finally settle below the back current, &c., thus preventing all undermining of the foundation- 20 mat. All river-bottoms do not require this device, while others will require two or more lengths of flexible mat, as shown in the drawings.

I am aware that prior to my invention 25 gravity-dams have been made consisting of a combination of a foundation-mat provided with a breastworks erected thereon and a dam superstructure. I therefore do not claim such a structure broadly; but

30 What I do claim as my invention, and desire to secure by Letters Patent, is—

1. In a dam the combination of a foundation-mat, having the lower sills run lengthwise with the dam, and the upper sills at 35 right angles to the same; and two plank floors laid on said sills, the lower floor being water-tight, and extending upstream several feet farther than the upper floor, and having a coffer-dam formed at the downstream edge of 40 said mat to dam up the water on top of mat.

2. In a dam structure the combination of a foundation-mat constructed as described, and provided with a breastworks erected along the upstream edge of upper mat-floor, and

resting on the lower floor, being sustained by 45 a cleat secured to the lower floor, or a brace back against the deck of dam, and filled above with gravel or other materials, substantially as specified.

3. In a dam the combination of a foundation-mat, a breastworks erected thereon, and rigidly secured thereto; and a dam superstructure having a deck composed of grooved plank laid an inch or so apart, with a tongue of dry wood inserted tightly in said groove 55 to be acted upon by the hydraulic pressure, substantially as described.

4. In a dam, the combination of a foundation-mat, a breastworks erected thereon, a coffer-dam erected on the mat to cause said 60 mat at all times to be submerged, a dam superstructure attached to said mat, sustaining the impounded water, and having a deck composed of grooved plank put together with a dry-wood tongue, an opening in either or 65 both abutments at end of dam to allow the free admission of air or objects into the interior of dam superstructure, substantially as described.

5. In a dam, the combination of a foundation-mat, a breastworks erected thereon, a dam superstructure having a deck of grooved plank fitted with wooden tongues and attached rigidly to said mat, openings at one or both ends of dam for the admission of air 70 or objects, and a flexible mat composed of a succession of wooden boxes filled with heavy materials strung on rods or chains, and attached to the downstream edge of the foundation-mat by chains or bolts, so that the 80 whole series of boxes forms a continuous heavy and flexible mat extending the entire length of the dam, substantially as described.

R. C. BEARDSLEY.
